UNITED STATES PATENT OFFICE.

WILLIAM D. P. AIMS, OF PHILADELPHIA, PENNSYLVANIA.

PETROLEUM STILL.

Application filed September 30, 1920. Serial No. 413,705.

To all whom it may concern:

Be it known that I, WILLIAM D. P. AIMS, a citizen of the United States, residing at Philadelphia, in the county of Philadelphia and State of Pennsylvania, have invented certain new and useful Improvements in Petroleum Stills, of which the following is a specification.

The principal objects of the present invention are, first, to provide for continuous distillation; second, to provide for inspection of the distilling operation; third, to provide for accurate and flexible regulation of temperatures; fourth, to provide for replacing, exchanging and adjusting the working parts of the still; fifth, to provide a still for satisfactory and economical use in refining petroleum; and sixth, to provide for progressive distillation in successive stages in an internally heated still. Other objects of the invention will appear from the following description at the end of which the invention will be pointed out and claimed.

A still embodying features of the invention is illustrated in the accompanying drawings forming part hereof and in which—

Figure 1, is an elevational view, with one of the sides removed.

Fig. 2, is a horizontal sectional view showing parts in plan.

Fig. 3, is a view drawn to an enlarged scale and showing one of the heaters.

Fig. 4, is a diagrammatic view, shown in transverse section, of parts of the still, and

Fig. 5, is an end view of some of the parts shown in Fig. 4.

In the drawings 1, is a closed casing or cabinet of heat insulating material and it is shown as rectangular and mounted on feet 2, but the shape may be varied. This casing is provided at its top with an offtake 3, for the distillate and at its bottom with an offtake 4, for the residuum, and transparent windows 5, in its rear wall are shown. Confined within the casing 1, there is a series of heaters 6, arranged one above the other, and alternated with a series of troughs 7, having slits 8, in their bottoms, so that the crude petroleum or other material in flowing from one heater to the underlying trough and thence to the top of the next underlying heater is progressively distilled in successive stages, the distillate passing out at 3, and the residuum passing out at 4, and the operation may be viewed through the windows 5. As

shown in Fig. 3, each heater consists of a section of pipe having caps 9 and 9^a, applied to its ends, and each trough 7, is fitted at its ends to these caps 9 and 9^a, leaving space between the troughs and the sections of pipe for the passage of the material being distilled. 10, are blocks arranged one above the other for supporting the troughs and heaters in the described superposed relation. 11, is an upright header or pipe arranged in the casing or cabinet 1, and to which superheated steam or the like is supplied by the valved pipe 12, fitted with a gage 13. 14, is a pet or drum cock connection for this pipe 11. 15, is an upright exhaust or offtake pipe arranged in the casing or cabinet 1, and provided with a gage connection 16, and with a discharge connection 17. The heaters 6, are connected across or between these pipes 11 and 15, although not in line with them, Fig. 2, and since the connections are alike a description of the connections of one heater will suffice. 18, is a branch pipe from the header 11, and it is provided with a valve 19, whose stem 20, is operable from the exterior of the casing and with a coupling or union 21. From the coupling 21 to the cap 9, of the heater extends a curved pipe 22. The connections from the heater, or more accurately the cap 9^a thereof, to the outlet header 15, are the same as those just described, and they are therefore designated 18^a, 19^a, 20^a, 21^a and 22^a. The purpose of the couplings 21 and 21^a, is to permit of the removal of one or more heaters and of their replacement by a heater or heaters of different sizes. Each heater is shown as equipped with a pyrometer 23, having its electrical couple 24, arranged therein, and extending outside of the casing or cabinet. Petroleum or other material to be distilled is introduced at 25, Fig. 4, into a box 26, confined within the casing 1, and supported on the headers or pipes 11 and 15. This box 100 is vented as at 27, and is provided at its bottom with a slit 28, aligned with the upper surface of the top heater 6. 29 is a plug valve operable by a stem 30, accessible from the exterior of the cabinet 1, and adapted to control the flow through the slit 28. The slit form of the openings for the passage of the material being distilled insures constant flow and avoids stoppage. 31, is a safety valve arranged at the top of the casing or cabinet 110 1. By removing one of the walls of the cabinet or casing 1, access may be had to the

interior for the purpose of making repairs and renewals which can be readily effected since all of the parts are readily accessible.

The mode of operation may be described 5 as follows:

The flow of superheated steam through the heaters 6, from the pipe 11, to the pipe 15, is regulated to obtain and maintain the exact heat required at each heater or cylinder 6, and for this purpose the gages 13 and 16, may be referred to and use may be made of the pyrometers 23, and of the various valves including 20 and 20^a, and the inflow 10 of oil and outflow of residuum are adjusted by the valves 30 and 4, so that the distillation is continuous and is carried on at any temperature desired and the distillation 15 may be observed through the windows 5 and regulated if desired.

The interior of the cabinet or casing 1, is of course as hot as may be required and there is ample room or space all around the heaters and their connections for the escape 20 of the distillate given off progressively as the petroleum or other material is heated in stages while flowing down over the heaters. The valve 4, is so regulated that enough of 25 the residuum is retained in the bottom of the casing to provide a seal for the distillation 30 late which escapes at 3.

It will be obvious to those skilled in the art that modifications may be made in details of construction and arrangement without departing from the spirit of the invention 35 which is not limited as to such matters or otherwise than as the prior art and the appended claims may require.

I claim:

1. A still comprising the combination of a 40 heat retaining casing or cabinet having top and bottom outlets for the distillate and residuum respectively, a series of superposed internally heated heaters and slit-bottom troughs alternated with the heaters and arranged in the casing or cabinet and spaced from the side walls thereof, valves operable from the exterior of the casing and appertaining to the respective heaters for regulating the heat of the heaters independently, 45 and means for introducing the material to be distilled onto the top heater, substantially as described.

2. A still comprising the combination of a heat retaining casing or cabinet having at 55 its top a distillate outlet and at its bottom a residuum outlet, vertical headers arranged in the casing and spaced from the side walls thereof and provided with valved pressure gauge and drain connections, a feed box 60 mounted at the top of the headers and provided with an elongated slit plug valve operable from the exterior of the casing to supply the material in sheet form, a series of

superposed heaters each connected to the headers and each provided with valves operable from the exterior of the casing and provided respectively with pyrometers to indicate the temperature of the heaters independently, and slit bottom troughs alternated with the heaters.

3. A still comprising the combination of a heat retaining casing or cabinet having at its top a distillate outlet and at its bottom a residuum outlet, vertical headers arranged in the casing and spaced from the side walls thereof and provided with valved pressure gage and drain connections, a feed box mounted at the top of the headers and provided with a slit-plug valve operable from the exterior of the casing, a series of superposed heaters each connected across the headers and provided with valves operable from the exterior of the casing and with pyrometers, said heaters having end caps, split-bottom troughs alternated with the heaters and engaging the caps, and blocks for detachably supporting the troughs and caps whereby the heaters and troughs are made interchangeable as units without disturbing the rest of the apparatus, substantially as described.

4. A still comprising the combination of a heat retaining casing or cabinet having at its top a distillate outlet and at its bottom a residuum outlet, vertical headers arranged in the casing and spaced from the side walls thereof and provided with valved pressure gage and drain connections, a feed box mounted at the top of the headers and provided with a slit plug valve operable from the exterior of the casing, a series of branch connections extending laterally from the headers and provided with couplings, a series of heaters detachably connected with the couplings and provided respectively with valves operable from the exterior of the casing and with pyrometers for each heater, and slit bottom troughs alternated with the heaters, substantially as described.

5. A still comprising in combination a casing or cabinet, a heated structure arranged in and spaced from the side walls of the casing and including spaced horizontal cylindrical heaters over which the material to be distilled flows in the form of a flat stream commensurate in width with the length of the heaters and by which it is progressively distilled in stages, means accessible from the exterior of the casing for controlling the temperature of the heaters independently of each other, and devices for maintaining a continuous flow of material in flat stream form whereby clogging is avoided, substantially as described.

WILLIAM D. P. AIMS,
